UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

RADIOSIGNALING SYSTEM.

1,304,296.

Specification of Letters Patent. Patented May 20, 1919.

Application filed December 2, 1916, Serial No. 134,804. Renewed November 8, 1918. Serial No. 281,741.

To all whom it may concern:

Be it known that I, CHARLES LE G. FORTESCUE, a subject of the King of England, and a resident of Pittsburgh, in the county 5 of Allegheny and State of Pennsylvania, have invented a new and useful Improvement in Radiosignaling Systems, of which the following is a specification.

My invention relates to systems employed 10 for signaling by means of electric waves that are projected through space without the use of conducting wires.

More particularly, my invention relates to improvements in space-signaling or radiotelegraph systems that embody means for controlling the high-frequency oscillating circuits thereof which are supplied with energy from alternating-current sources.

It is recognized that, to render the receiving apparatus of a radio system most effective, the impulses impressed upon the receiving circuit should occur at the rate of approximately 1000 impulses per second, which corresponds to the frequency or pitch 25 of a tone of good audibility. To insure uniformity in the production of the tone in the receiving circuit and also the production of a note having a constant pitch, these impulses should be produced at regular, as 30 well as frequent, intervals. Moreover, the loudness of the tone produced in the receiving circuit depends upon the amplitudes of the impinging wave trains. This last property is secured over long distances by generating wave trains at the sending station that are only slightly damped or possess a 35 low decrement. It is apparent, therefore, that the wave trains originating in the sending station should be produced at regular 40 intervals and with suitable frequency, as well as, with high initial amplitudes in order to radiate from the antenna a series of wave trains that may be projected over wide spaces and be instrumental in producing, in the receiving apparatus, audible 45 notes of constant pitch or uniformity.

An object of my present invention, therefore, is to provide means for accomplishing the aforementioned results, whereby radiations that are only slightly damped may emanate from the antenna of a wireless sending station. At the same time, the wave trains projected into space may be

produced at a high rate and uniform frequency in order to insure the production of 55 a uniformly pitched and audible note in a distant receiving station. I accomplish these results without using a high-frequency alternator but by employing the usual Hertzian oscillator.

For a better understanding of the nature and scope of my invention, reference may be had to the following description and the accompanying drawing in which Figure 1 is a diagrammatic view of a radio-telegraph 65 system that embodies a form of my invention, and Fig. 2 is a similar view for illustrating one arrangement for the apparatus comprising the circuits of Fig. 1.

In Fig. 1, a source 1 of alternating current is connected, by means of conductors 2 and 3, to a primary winding 4 of a transformer 5. One secondary winding 6 of the transformer is connected in closed circuit with an adjustable condensive reactance element 7. The windings 4 and 6 of the transformer are closely magnetically linked with each other. The capacity of the condensive reactance element 7 is so chosen that its effect in the circuit comprising the primary winding 4 will, under certain circumstances, completely compensate for the inductive reactive drop in said circuit when subjected to the flow of alternating currents having the frequency of those generated by the 80 source 1. In other words, the circuit comprising the primary winding 4 may operate, in certain instances, at unity power-factor since the condenser 7 will completely 85 compensate for the inductive reactance obtaining therein.

A secondary winding 8 of the transformer supplies power to a high-frequency oscillating circuit 9. The circuit 9 comprises an oscillation producer 10, an adjustable condensive reactance element 11 and a primary winding 12 of an oscillation transformer 13, which may be of any usual form commonly employed in connection with radio systems. A secondary winding 14 of the oscillation transformer has one of its terminals grounded at 15 and the other connected, through an adjustable inductance device 15, to an antenna or electrical wave radiator 16.

The windings 8 and 4 of the transformer

5 are loosely magnetically linked with each other and, therefore, a leakage flux will obtain between the primary or inducing winding 4 and the said secondary winding, under 5 certain operating conditions.

The windings 12 and 14 of the transformer 13 may be loosely or closely coupled. The coupling action is augmented when the primary and secondary circuits of the transformer 13 are in resonance. Again, if proper quenching of the sparks generated by the oscillation producer 10 is effected, the oscillations in the circuit comprising the primary winding 12 will discontinue after a very short time-interval. The secondary circuit, therefore, will continue to oscillate at its natural frequency and with its natural damping just as if the primary circuit did not exist.

20 The oscillation producer 10, in this instance, is shown as comprising a pair of spaced electrodes 17 and 18 which are adjustable. The oscillation producer 10 may be any of the usual forms commonly employed in connection with wireless systems.

The capacity of the condensive element 11 is so chosen that the circuit comprising said element, the secondary winding 8 and the primary winding 12 of the oscillation transformer 13 is in resonance with the circuit comprising the primary winding 4 of the transformer 5, when the oscillation producer 10 is inactive. In other words, series resonance conditions are established between these two circuits since the condenser 11 inserts a condensive reactance that resonates with the inductive reactance inserted by reason of the leakage flux obtaining between the windings 4 and 8. Of course, these series resonance conditions obtain for the normal frequency of the generator.

To produce high-frequency oscillations in the primary circuit of the oscillation transformer 13, the spark gap between the electrodes 17 and 18 of the oscillation producer 10 is disrupted by the voltages impressed thereupon by the secondary winding 8. The initial breakdown being thus effected, high-frequency oscillating currents will flow in the primary winding 12 by reason of the rapid charging and discharging of the condenser 11. The amplitudes of the high-frequency currents thus generated are constantly decreasing in value because of the damping action of the primary and secondary circuits. This is a usual way of generating electromagnetic oscillations which are to be radiated from the antenna of a radio system. It will be noted that, each time a discharge is effected between the electrodes 17 and 18, a wave train will be propagated into space from the antenna 16. Each wave train thus emanated will produce a single impulse in the receiving apparatus of a distant receiving station.

To produce audible notes of proper and uniform pitch, as well as loudness in the receiving apparatus, it is desirable to generate wave trains in the order of 1000 per second, with uniform regularity and frequency. To accomplish this, the condenser 11 should be instantaneously recharged after each breakdown of the spark-gap of the oscillation producer 10. In other words, the time-lag between the exciting current traversing, and the resulting flux generated by, the inducing winding 4 and between said flux and the production of a sufficient voltage in the secondary winding 8 to break down the spark-gap of the oscillator 10 should be substantially zero.

The condenser 7, by reason of its association with the winding 6, compensates for the inductance obtaining in the circuit of the primary winding 4 only when the oscillation producer 10 is active. As a result, the maximum flux threading through the primary winding 4 is coincident in time with the maximum voltage or the peak of the alternating-current wave generated by the alternator 1, when the condenser 11 is rapidly charging and discharging through the oscillation producer 10.

When the voltage obtaining in the secondary winding 8 is sufficient to break down the spark-gap of the oscillation producer 10, the condenser 11 will discharge through the oscillation producer, thereby generating high-frequency oscillations in the oscillating circuit 9. Simultaneous therewith, the secondary winding 8 will be short circuited by reason of the spark discharge obtaining in the oscillation producer. At the same time, however, the circuit comprising the primary winding 4 will operate at unity power-factor by reason of the action of the condenser 7. The value of the flux generated by the primary winding 4 is, therefore, independent of the conditions obtaining in the high-frequency oscillating circuit 9.

When these conditions exist, the voltage induced in the secondary winding 8 is likewise coincident in time with the magnetic flux generated by the primary winding 4, because the circuit comprising the short-circuited secondary winding 8 is in resonance with the circuit comprising the primary winding 4. In other words, this combination of circuits is tuned to the frequency of the source of supply 1.

The high-frequency currents generated in the oscillating circuit 9 are substantially precluded from flowing through the secondary winding 8 because of the large reactance obtaining in said winding. By reason of the large magnetic leakage between the windings 4 and 8, the high-frequency currents are also substantially precluded from inducing any currents in the primary winding 4. The energy of the high-frequency currents is,

therefore, confined to the high-frequency circuit 9 and the circuit comprising the antenna 16.

From the foregoing description, it will be apparent that the wave trains are rapidly generated, since the conditions obtaining in the secondary winding 8 are in accurate time-phase with the conditions obtaining in the primary winding 4. Again, the wave trains are rapidly produced with high initial amplitudes and, moreover, they possess a low decrement since the high-frequency oscillations are confined to the high-frequency oscillating circuit 9.

15 In Fig. 2, I have shown, diagrammatically, a structure for obtaining the desired relations between the windings 4, 6 and 8 of the transformer 5 of Fig. 1. It will be noted that the primary winding 4 is disposed on 20 the same core leg as the secondary winding 6. The windings 4 and 6 are, therefore, closely magnetically linked with each other. The secondary winding 8 is disposed on a second core leg. Magnetic shunts 20 and 25 21 provide means for increasing or varying the magnetic leakage between the primary winding 4 and the secondary winding 8. By properly positioning the magnetic shunts 20 and 21, series resonance may be established 30 between the winding 4 and the winding 8 in combination with the condensive reactance element 11. The primary winding 4 is impressed with alternating currents of the proper frequency, in this case, the frequency 35 of the currents generated by the alternator 1.

While I have shown and described one embodiment of my invention, I desire that only such limitations shall be imposed there-upon as are indicated in the appended 40 claims.

I claim as my invention:

1. In a system of radio-signaling, the combination with an alternating-current source of supply and a high-frequency oscillating circuit, of a transformer for interconnecting said circuit to said source, said transformer comprising a primary winding which is connected to said source, a secondary winding closely magnetically linked 45 with the primary winding, a second secondary winding loosely magnetically linked with the primary winding, a condensive reactance element connected in circuit with said first secondary winding, and means for connecting the high-frequency oscillating circuit to said second secondary winding.

2. The combination with a source of alternating-current supply and a high-frequency oscillating circuit comprising an oscillation 50 producer and a condensive reactance element, of a transformer for interconnecting said source and said oscillating circuit, said transformer comprising a primary winding that is connected to said source, one secondary winding that is closely magnetically

linked with the primary winding, a condensive reactance element connected to said secondary winding, and a second secondary winding loosely magnetically linked with the primary winding, said second secondary 70 winding being connected in shunt to said oscillation producer and in series with said first condensive reactance element.

3. The combination with a source of alternating-current supply and a high-frequency 75 oscillating circuit comprising a condenser and an oscillation producer, of a transformer for interconnecting said source and said oscillating circuit, said transformer comprising a primary winding, a secondary winding closely magnetically linked therewith, a second secondary winding loosely magnetically linked therewith and connected to the oscillating circuit, the capacity of said condenser of the oscillating circuit being of 80 such value as to establish series-resonance conditions between said primary winding and the circuit comprising said second secondary winding, under normal conditions, and a condenser connected in circuit with 85 said first secondary winding to compensate for the inductive reactance of the circuit comprising said primary winding when the resonance conditions between the primary winding and said second secondary winding 90 are disturbed.

4. The combination with a source of alternating-current supply and an energy-consuming circuit comprising a condensive reactance element, of a transformer for interconnecting said source and said circuit with 100 each other, said transformer comprising a primary winding, a secondary winding which is loosely magnetically coupled therewith and also connected in circuit with said 105 condensive element whereby series resonance conditions may obtain between the circuits comprising said transformer windings, a second secondary winding closely magnetically linked with said primary winding, and a condensive reactance element connected in circuit with the second secondary winding for establishing resonance conditions in the circuit comprising the primary winding when the resonance conditions between the 110 primary winding and the said first secondary winding are disturbed.

5. The combination with a supply circuit, a transformer comprising a primary winding, a secondary winding closely magnetically linked therewith, and a second secondary winding loosely magnetically linked therewith, of a condenser connected in circuit with said second secondary winding to establish resonance conditions between the 115 primary and said secondary windings, and another condenser connected in circuit with said first secondary winding to compensate for the inductive reactive drop in the circuit comprising the primary winding when reso- 120

nance conditions between the primary winding and said second secondary winding are destroyed.

6. The combination with a supply circuit, 5 a transformer comprising a primary winding, a secondary winding closely magnetically linked therewith and a second secondary winding loosely magnetically linked therewith, of a condenser connected in circuit with said second secondary winding to establish series resonance conditions between the primary and second secondary windings, and a condenser connected in circuit with said first secondary winding to establish 10 resonance conditions in the circuit comprising the primary winding when the series resonance conditions between the primary winding and said second secondary winding are disturbed.
- 15 7. The combination with a supply circuit, a transformer comprising a primary wind-
- ing, a secondary winding closely magnetically linked therewith and a second secondary winding loosely magnetically linked therewith, of a condensive reactance element 25 connected in circuit with the said second secondary winding to completely neutralize the effects of the leakage flux between the primary winding and said second secondary winding, and a condensive reactance element 30 connected in circuit with said first secondary winding for completely neutralizing the inductive reactive drop in the circuit comprising the primary winding when the condensive element connected in circuit with said second secondary winding fails to maintain resonance conditions between the primary winding and said second secondary winding. 35
- In testimony whereof, I have hereunto subscribed my name this 23rd day of Nov. 40 1916.

CHARLES LE G. FORTESCUE.
